UNITED STATES PATENT OFFICE.

MOSES MOSLER, OF CINCINNATI, AND CARL BARTELS, OF HAMILTON, OHIO, ASSIGNEES
TO THE MOSLER SAFE COMPANY, OF NEW YORK, N. Y.

GRINDING-MACHINE.

1,153,510.

Specification of Letters Patent.

Patented Sept. 14, 1915.

Application filed July 2, 1915. Serial No. 37,650.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Grinding-Machines, of which the following is a specification.

This invention, pertaining to improvements in grinding machines, relates particularly to improvements in machines for grinding the doors and door-jams of safes of the round door type.

The improvements will be readily understood from the following description taken in connection with the accompanying drawings in which:—

Figure 1 is a plan of a grinding machine exemplifying our improvements, the machine being illustrated as operating upon the door-jamb of a safe illustrated in the plane of line *d* of Fig. 2: Fig. 2 a side elevation of the machine under the same conditions: Fig. 3 a side elevation of the shifting mechanism, the lathe-arbor appearing in vertical section in the plane of line *a* of Figs. 1 and 2: Fig. 4 a side elevation of the shifting-fork, parts appearing in vertical section in the plane of line *b* of Figs. 1 and 2: Fig. 5 a rear view of a portion of the shifting mechanism, a part appearing in vertical section in the plane of line *e* of Fig. 3: and Fig. 6 a vertical longitudinal section of the pulley of the grinding-spindle, in the plane of line *f* of Fig. 1.

A diversity of scales is employed in the drawings.

Our machine, generally considered, embodies a bed; a fixed headstock thereon; an arbor journaled therein and carrying a chuck; a carriage mounted on the bed; and a spindle supported by the carriage and carrying the grinding wheel.

In the drawings:—1, indicates the bed provided with guide-ways; 2, a headstock fixedly mounted on one end of the bed; 3, the outer headstock bearing for the arbor; 4, the inner headstock bearing for the arbor; 5, the arbor mounted for rotary and end-wise movement in the headstock bearings; 6, a chuck carried by the arbor and adapted to support the article with which the grinding wheel is to deal, our present contemplation being that the article to be dealt

with will be the body or door of a safe of round door type, the illustration showing the chuck as carrying a safe-body: 7, an internal gear fast with the chuck: 8, a fixed countershaft journaled in the headstock parallel with the arbor: 9, a pinion carried by the first countershaft and engaging the internal gear of the chuck: 10, a second countershaft journaled in the headstock: 11, a pinion loose on the first countershaft: 12, a sleeve loose on the first countershaft and having the pinion 11 secured to it: 13, a gear fast on the second countershaft and engaging pinion 11: 14, a pinion fast on the second countershaft: 15, a gear fast on the first countershaft and engaging pinion 14: 16, a pulley loose on sleeve 12 and provided with a clutch-hub: 17, a second pulley loose on sleeve 12 and provided with a clutch-hub, the two clutch-hubs facing each other: 18, a clutch splined on sleeve 12 and adapted, when thrown one way or the other, to lock pulley 16 or pulley 17 to the sleeve and, consequently, to pinion 11: 19, a pivoted shifting lever provided with a fork engaging clutch 18 so that the lever may be oscillated to shift the clutch into engagement, selectively, with either of the two pulleys: 20, the pivot on which lever 19 oscillates, this pivot being supported by a portion of the headstock: 21, pins or rollers projecting downwardly from the inner end of clutch-lever 19, these pins or rollers being disposed in lever 19 at a considerable distance from each other in the line of the axis of the arbor, the end of the clutch-lever which carries these rollers projecting inwardly to near the arbor: 22, an arm supported by a portion of the headstock and disposed below the clutch-lever and projecting inwardly between rollers 21 in such manner that the oscillation of arm 22 will cause the arm to engage one of the rollers 21, the particular one of the rollers engaged being dependent upon the direction of movement of the arm: 23, the pivot on which arm 22 oscillates, this pivot being fixedly supported by a portion of the headstock: 24, a pair of side acting collars or cams carried by arbor 5 and adapted to be longitudinally adjusted thereon, these two cams being in such position as to straddle the vertical plane of the inner end of arm 22: 25, a pin or roller projecting outwardly from the end of arm 22 and adapted to be engaged by the

- collars or cams 24: 26, a nut fixedly carried by the headstock and surrounding the outer end of the arbor: and 27, a threaded leader secured to the arbor and engaging nut 26 so that as the arbor turns it will be moved endwise relative to the headstock.
- The design is that the chuck, with the work carried by it, will turn in one direction, through one or more rotations, traveling endwise during its turning, and that the motions of the chuck shall then be reversed as to rotation and endwise movement, and so on and on. In case a thread of a given pitch is to be ground upon the work then the thread of leader 27 is to have the same pitch, and provisions are to be made for the substitution of leaders in case a variety of threads are to be produced in the machine. Nut 26 may be a complete nut to fit the leader but it is our preference that only the upper half of the nut be a real nut with threads in it, the lower half being merely a bearing for the outer portion of the threads of the leader.
25. One of pulleys 16 is to be driven by open belt and the other by cross belt. Assuming clutch 18 to be in neutral position the two pulleys will turn idly on sleeve 12 and the arbor and chuck will be at rest. If, now, by manipulating clutch-lever 19, clutch 18 be thrown into engagement with one of the pulleys, that pulley will become locked to the sleeve 12 and, consequently, to pinion 11 which is fast with the sleeve. The result is 30 that the gearing will cause rotary motion to be transmitted to the chuck in a certain direction. The arbor, in rotating, moves endwise by reason of leader 27 working through nut 26.
40. When the endwise movement of the arbor has proceeded a certain distance, for which the collars 24 have been adjusted, one of the collars will engage roller 25 of arm 22 and shift that arm sidewise and bring about a 45 sidewise shifting of clutch-arm 19 and cause the clutch to leave the pulley with which it is engaged and to engage with the opposite pulley whereupon the arbor and chuck turn in the opposite direction of rotation and endwise movement. The chuck, together with the work carried by it, therefore will obviously move rotarily and longitudinally first in one direction and then the other, the times between the reversal of motion being 50 dependent upon the adjustment of collars 24 along the arbor.
- For the character of work practically dealt with by us, the grinding of the doors and door-jams of safes, we prefer that the 60 reversal of the direction of motions be effected at the end of each one and one quarter rotation of the chuck, an excess over one turn is essential in order that the grinding wheel shall lap over its work and not produce a seam in its work.

Collars 24 could bring about the desired reversals of motions if they had no cam qualities but it is our desire that these collars have cam faces to engage pin 25 as it thus becomes possible to provide for reversals 70 of motion not dependent entirely upon the endwise movement of the arbor. In other words, by providing the collars with spiral cam faces, as illustrated, the shifting of arm 22 bringing about the reversals of motions, 75 may be controlled, at proper points, by the rotation of the collars as well as by their endwise motion. The spiral cams of the collars also permit of a more delicate adjustment for the shifting instant than would be 80 possible if the endwise motions only of the collars were depended upon.

It is well known that motion-reversing devices of the character thus far described, are open to the objection of stopping at the 85 neutral point and thus not completing the reversal. We overcome this by the not unusual scheme illustrated in Fig. 5 in which 51 is a wedge-shaped spring plunger engaging a corresponding wedge on arm 22. 90 While arm 22 is being urged to one side by one of the collars on the arbor, the wedge 51, is being depressed, and the instant the apex of the moving wedge passes the apex of wedge 51 then the re-action of spring wedge 95 51 causes arm 22 to instantly move sidewise and engage a roller 21 of the clutch-arm and withdraw the clutch from the pulley with which it is in engagement and throw it into engagement with the other pulley. 100

At such times as the machine is at rest, as in placing, adjusting, or in moving the work, it is of high importance that the clutch cannot be so shifted as to start up the machine. We will now describe the construction looking to this end.

Proceeding with the drawings: 28, indicates an aperture through clutch-lever 19 normally concentric with fixed pivot 23 of arm 22, the upper end of pivot 23 bearing fixedly a bearing for an eccentric mechanism: 29, a detent collar sliding vertically on pivot 23 and adapted to enter aperture 38: 30, an eccentric mechanism consisting of a shaft journaled in the upper portion of 110 pivot 23, a lever on that shaft, and outwardly extending eccentric pins engaging slots in ears on collar 29: 31, a link projecting from the arm of the eccentric mechanism: and 32, a hand-lever connected with 115 link 31 and adapted to hold the eccentric mechanism in active or idle position.

Normally detent collar 29 will be in the position indicated in Fig. 4, and out of office, and clutch-lever 19 will be free for the 120 performance of its office. If, now, hand-lever 32 be properly moved while the clutch-lever is in neutral position, or moving past the neutral position, detent collar 29 will be moved down into aperture 28 and while 125

the detent collar remains in this position the clutch-lever is locked in neutral position. The hand-lever 32 is preferably provided with means for locking it in either the active or idle position.

5 We will now describe the mechanism directly associated with the grinding wheel. Proceeding with the drawings: 33, indicates a carriage sliding on the ways of the bed: 10 34, a slide adapted for cross movement on the carriage, this slide bearing a vertically open cylinder which is vertically slit and provided with a clamp: 34^a, a compound rest swiveled for angular adjustment in 15 slide 34: 35, a housing longitudinally adjustable on the compound rest: 35^a, a screw for adjusting housing 35 on the compound rest: 36, ears projecting upwardly from housing 35: 37, a wheel-housing trunnioned 20 in ears 36: 38, a wheel spindle journaled in the wheel housing: 39, an adjusting device for regulating and securing the adjustment of the wheel housing relative to housing 35: 25 40, a grinding wheel carried by the inner end of wheel spindle 38 and adapted for the performance of such grinding work as the machine may be called upon to perform: 41, a pair of ears carried by housing 35: 42, a pulley having exteriorly projecting journals running in ears 41: 43, shallow longitudinal grooves in wheel spindle 38 and at about the longitudinal center of pulley 42: 44, screws disposed radially in pulley 41 and having concavities at their inner 30 ends: 45, a ball disposed in the concavity of each screw 44 and engaging a corresponding groove 43 in wheel spindle 38: 46, mechanism mounted on the carriage 43 and adapted for the adjustment of the carriage 35 to and from the chuck, this mechanism being not necessarily unlike the shifting mechanism usually provided on lathe carriages: 47, a binder to secure the lathe carriage to the bed of the machine in adjusted position, if such securing shall be needed: 48, a 40 shaft journaled across the carriage and provided with a hand-wheel for turning it: 49, a screw mounted in the carriage and adapted for moving slide 34 across the carriage, after the usual manner of ordinary engine lathes: 50, gearing, of an obvious character, connecting shaft 48 with screw 49: and 51, the neutralizing wedge device heretofore referred to.

55 The principal purpose of our machine is the grinding of screw threads on safe doors and in the door-jambs of safes, and especially on safes and doors of such peculiarly resisting metal as manganese steel.

60 Our machine is, however, adapted for the grinding of short cylindrical surfaces, either interior or exterior. The chuck which we illustrate is of an obvious character and is to be considered as merely exemplifying.

If a short cylindrical surface, either interior or exterior is to be ground, then wheel housing 37 is to be so adjusted and secured that the axis of the wheel spindle will be parallel with the axis of the arbor. 70 It may be well to here state that our preference is that the adjusting device 39 for varying the horizontal angle of the wheel spindle be of a solid character not within itself adjustable. Instead of an adjusting 75 screw arrangement we prefer the employment of selective blocks of definite height to be interposed between housing 35 and housing 37, the blocks being of such thickness that, when clamped between the two housings, the wheel spindle will be either horizontal or at such angle as will bring the grinding wheel tangent to the angle of the thread to be ground.

Continuing the assumption that it be desired to grind a short cylindrical surface, the wheel-spindle having been adjusted to and secured in a horizontal position, the carriage is to be moved to bring the grinding wheel to near the beginning of the surface to be ground. Detent collar 29 is now to be thrown out of action and the clutch-lever so manipulated as to put one of the pulleys into driving action. The chuck with its work now starts to revolve in a 90 certain direction, and at the same time it moves axially, and the selected clutch should be the one which will cause the work to move axially toward the wheel. The rotary and endwise motion of the work proceeds until a collar on the arbor brings about the shifting of the clutch whereupon the work turns and moves axially in the opposite direction, and so on and on until the work is completed, it being understood, of course, that during this operation the slide will be adjusted at suitable intervals so as to keep the wheel in proper action upon the work. In this operation the axial movement has been made by the work and not by 100 the wheel.

In grinding operations of the character for which our machine is designed, there is no such end thrust as is incident to the operation of ordinary cutting tools, and we 115 find in practice that as a general thing the carriage with its appurtenances will remain in whatever position it may have been shifted to upon the bed of the machine and that binder 47 to lock the carriage to the 120 bed is generally non-essential. When the work is completed then the clutch-lever is locked in the neutral position thus preventing the turning of the chuck, and the work may be removed, and a new job put into the 125 chuck.

In the grinding of screw threads on manganese steel castings it is not customary to grind the thread from the solid, though, of course, it can be done. Our preference is 130

that the thread be cast and that the grinding of the thread be employed as a finishing step.

Assume that a thread is to be ground in the doorjamb of a safe, such as illustrated in the drawings. The leader 27 is to have a pitch corresponding with the pitch of the thread to be ground in the work. In grinding the interior periphery of the threaded opening the adjustments and manner of operation will be as has been heretofore described with reference to the grinding of a cylindrical surface. But when it comes to the grinding of the sides of the thread then the axis of the wheel spindle must be so adjusted that the side of the wheel will be tangent to the angle of the thread being ground. Absolute coincidence between the side of the wheel and the side of the thread cannot be secured, owing to the plane character of the side of the wheel and the helical character of the side of the thread, but we find in practice that, notwithstanding this, the work can be accomplished with entire satisfaction.

Assuming, now, that a thread is to be ground upon the work, either interiorly or exteriorly, the pitch of leader 27 having the same pitch as the thread to be ground. The wheel-housing is now to be adjusted and secured to housing 35 at such angle that the side of the grinding wheel will coincide, as nearly as practicable, with the side of the thread to be ground, and housing 35 is to be adjusted axially of the work till the side of the wheel is in the plane of the side of the thread which is to be ground, allowance being made for the depth of cut which is to be taken by the wheel. The work is now to be started into rotation and axial movement, and the grinding wheel moved radially of the work and the grinding operation upon the side of the thread is to proceed, the work changing its direction of rotation and direction of axial motion at each complete longitudinal trip of the thread relative to the wheel, collars 24 having, of course, been properly adjusted for the reversals. The wheel is to be thinner than the space between the threads, and the grinding of the thread may be progressive radially of the thread, or, if desired, the wheel may enter the thread, if a previously cast thread is in hand, the full depth of the thread and operate against the full depth of the side of the thread. Eventually, the root of the space of the thread may be finished by the periphery of the wheel.

The grinding wheel spindle-pulley 42 might be fast upon the wheel spindle, and we have employed our machine in this manner, but by mounting the pulley in fixed bearings and connecting it with the wheel-spindle after the manner of a universal joint, as illustrated, we are able to maintain the pul-

ley in normal relationship with its driving belt notwithstanding the angular adjustments of the spindle which the pulley drives.

We have heretofore spoken of the reversal of the rotary motion of the work at the end of one and a quarter rotations, the excess over a full rotation being designed to avoid the possibility of a seam appearing in the grinding. In case of a thread there should be, between reversals of rotation, an excess of rotation over that required to complete the range of the thread. In other words, if there is but one complete turn of the thread there should be an excess of, say, a quarter of a turn to avoid possibility of seaming. In much of our practical work there is one and a quarter turn to the thread and in such case we so adjust the reversing mechanism as to produce, between reversals, an excess over such degree of rotation. The adjustment of collars 24 provides for any desired degree of excess over any given complete turns of the thread.

We ought to mention the fact that our machine, when constructed for its intended purpose, is of very considerable size, being in fact, a pit machine standing on a level considerably below the shop floor. The workman in operating the machine will generally stand on the carriage. It is for this reason that, instead of providing a handle on cross feed screw 49, the screw is geared to a hand wheel on a higher level.

We have thus far given particular attention to the grinding of threads, in which operation the work moves axially. In the grinding of cylindrical surfaces, as has been described, the work may move axially, or, if desired, the nut or the leader may be removed and the grinding wheel may be moved axially, by moving housing 35 of the compound rest or by moving the carriage. Owing to the lack of any interfering end thrust due to the grinding operation, there is no special necessity for locking the arbor against endwise motion during this operation. When tapers are to be ground then the arbor is to be left free from influence by the leader and its nut, by removing either, and the compound rest is to be swiveled to bring the axis of the wheel spindle at proper angle, and the axial movement of the grinding wheel is to be produced by the feeding movement of housing 35 on the compound rest. In much of the grinding upon safe-parts of manganese steel, the mode of procedure followed in the art of roll grinding, is preferably adopted by us, especially in the initial parts of the process, that is to say, the grinding wheel will be set and moved radially to complete one longitudinal portion of the surface and then moved away from the work and then moved longitudinally and then moved again to the work to grind a second portion, and so on,

the work being ultimately completed by performing the above successive operations with accuracy or by longitudinally moving the wheel along the surface to be ground.

5 The machine particularly set forth, is to be viewed merely as an exemplification of our invention. We have sought to set forth the principle of our invention and the best mode in which we at present contemplate 10 embodying that principle.

We claim:-

1. A grinding machine comprising within its mechanism, an arbor provided with a chuck, bearings in which the arbor may turn 15 and slide, a grinding-wheel adapted to operate upon work held in the chuck, a screw and nut device to serve in moving the arbor endwise during its rotation, and mechanism for reversing the rotary motion of the arbor, combined substantially as set forth.

2. A grinding machine comprising within its mechanism, an arbor provided with a chuck, bearings in which the arbor may turn and slide, a grinding-wheel adapted to 25 operate upon work held in the chuck, a screw and nut device to serve in moving the arbor endwise during its rotation, mechanism for reversing the rotary motion of the arbor, and adjustable collars mounted on the 30 arbor and adapted for the actuation of said reversing mechanism, combined substantially as set forth.

3. A grinding machine, comprising within its mechanism, an arbor provided with a 35 chuck, bearings in which the arbor may turn and slide, a grinding-wheel adapted to operate upon work held in the chuck, a screw and nut device to serve in moving the arbor endwise during its rotation, mechanism for 40 reversing the rotary motion of the arbor, adjustable collars mounted on the arbor and adapted for the actuation of said reversing mechanism, and cams upon said collars adapted to take part in the reversing operation 45 and permit the reversing operation to be controlled by the rotary as well as the endwise movement of the arbor, combined substantially as set forth.

4. A grinding machine comprising within 50 its mechanism, an arbor to carry the work to be ground, a pair of pulleys adapted to rotate said arbor and provided with clutch

hubs, a clutch serving to lock a selected one of the pulleys into transmission engagement with the arbor, a lever for throwing the 55 clutch into engagement with either pulley, an arm adapted to move said lever, collars carried by said arbor and adapted to move said arm, and spring wedge mechanism for throwing said arm and lever to an extreme 60 position when the arbor shall have caused the arm to pass the neutral point in its motion, combined substantially as set forth.

5. A grinding machine comprising within its mechanism, an arbor, a clutch-lever adapted by its oscillations to control the direction of motion of the arbor, a detent aperture in said clutch-lever, a detent collar adapted to enter said aperture and retain the clutch-lever in neutral position, and means for adjusting said detent collar to active or idle 70 position, combined substantially as set forth.

6. A grinding machine comprising within its mechanism, a headstock, arbor-bearings carried thereby, an arbor arranged to turn 75 and slide in said bearings, a threaded leader carried by the arbor, and a nut carried by the headstock and engaging said leader, combined substantially as set forth.

7. A grinding machine comprising within 80 its mechanism, a hollow pulley journaled in bearings, a grinding wheel spindle mounted for rocking motion within the hollow of said pulley and provided with longitudinal 85 grooves, and a circumferential series of balls carried by the bore of the pulley and engaging said grooves, combined substantially as set forth.

8. A grinding machine comprising within its mechanism, a carriage, a cross slide thereon, a compound rest swiveled in said cross slide, a grinding wheel housing carried by said compound rest, means for adjusting said grinding wheel housing at various horizontal angles to the compound rest, a grinding wheel spindle mounted in said housing, and means for rotating said spindle, combined substantially as set forth.
